UNITED STATES PATENT OFFICE.

IRVAN NECKERMAN, OF ANNAPOLIS, MARYLAND.

PUSH-BUTTON OPERATOR.

1,219,344.

Specification of Letters Patent. Patented Mar. 13, 1917.

Application filed November 25, 1916. Serial No. 133,518.

To all whom it may concern:

Be it known that I, IRVAN NECKERMAN, a citizen of the United States, residing at Annapolis, in the county of Anne Arundel and State of Maryland, have invented new and useful Improvements in Push-Button Operators, of which the following is a specification.

This invention relates to the class of devices ordinarily known as push buttons, and its purpose is to provide a device for actuating the push button from a point remote from the position occupied by the button itself. As is well known, it is customary to lead the wires of an alarm circuit or an annunciator circuit to a circuit closer which is usually in the form of the well known push button, and the latter is screwed to the support to which the wires are run and is within reach of the person who is to operate it. Conditions often arise, however, whereby the operator changes his position so that he can no longer reach the push button, and in the case illustrated herewith it is desirable for the operator to press the push button without moving his hand from the steering wheel of an automobile.

My invention may therefore be said to be a push button operator capable of any use to which it may be put. The following specification describes the preferred construction of this invention, with one modification thereof, reference being had to the accompanying drawings, wherein:

Figure 1 is a side elevation of the steering shaft and wheel of an automobile with a button on the shaft as usual in Ford machines, and my attachment applied so that this button can be pushed by an operator without moving his hand from the rim of the wheel.

Fig. 2 is a perspective view of the attachment alone.

Fig. 3 is a detailed view of a slight modification thereof.

In Fig. 1 I have employed the letter S to designate the steering shaft carrying the hand wheel W having a rim R, and B is the button ordinarily mounted on said shaft S in Ford machines. When this button is to be pressed by the operator, he must remove his hand from the rim R and reach a little farther down the shaft than usual, and when my invention is employed in this connection it enables him to press

the button without so removing his hand. This is, however, but one illustration of many uses to which this invention can be put.

Coming now to the details of the invention itself, the numeral 1 designates an arched bridge or yoke whose body is substantially U-shaped with lateral feet 2 through which may be passed screws or other fastening devices 3 for attaching this yoke to any appropriate member. In Fig. 1 I have shown the yoke disposed so that the feet may be attached to the steering shaft S by removing and reinserting the same rivets or screws 3 which hold the button B thereon, and when in place the body of the yoke overlies and protects or guards the button from accidental pressure by the knee or otherwise. Mounted upon or attached to one side of the yoke is a pair of ears 4 best seen in Fig. 2 to which at 5 is pivoted the extremity of an extension arm 6. From its pivotal point this arm leads across the interior of the yoke, through an elongated opening or slot 7 in the other side of the same, and is carried away any suitable distance and bent in any suitable manner as demanded by the exigencies of the case. Its remote or free end is herein shown as having a knob or handle 8 which in the adaptation shown in Fig. 1 underlies the rim R of the wheel W and in such position that the operator's thumb may bear against the same without the necessity for his removing his hand from the rim. I prefer to employ means for holding the arm out of contact with the button B, and in Fig. 2 such means is shown as a spring 10 secured at one end as at 11 to one side of the yoke and with its other end bearing against the arm 6 so as to hold the latter normally in the upper end of the slot 7, but the tension of this spring is such that it yields under pressure against the knob or handle 8 so that the arm can fall within the slot.

Within the yoke the said arm overlies the button B and it is quite possible to provide the arm with a projecting point or perhaps a screw 13 as illustrated in Fig. 2, so mounted therein that its head alines with the button B. When the attachment is applied as shown in Fig. 1, this screw is adjusted to be nearly in contact with the button when the arm lies in the upper end of the slot 7. Thereafter it is quite obvious that when

the operator desires to press the button he depresses the knob or handle 8, and the screw 13 presses the button and the alarm is given.

5 In Fig. 3 is shown a slight modification wherein the ears 4 and the spring 10 are omitted and the latter is replaced by part of the arm, a construction which may sometimes be preferred. In this case the extremity of the arm 6 is turned down and flattened as at 16 and tempered so as to give it resiliency, and, instead of pivoting it to the yoke, it is riveted thereto as at 15. I have made use of this view to show that the 10 attachment may be so located that the contact point or screw 13 overlies a button, the latter standing upright in this case. Although it is quite obvious that the length and shape of the arm is a matter of no importance to the invention, I would make it 15 rather pliable so that when the attachment is put into place the arm can be bent to carry the handle 8 to the desired point of use. I repeat that, although I have shown 20 and described the attachment as applied to the button on the steering shaft of a Ford automobile, I do not wish to limit it to this use.

25 What is claimed as new is:—

30 1. The herein described push button operator, the same comprising a yoke adapted to be secured over and out of contact with the push button and having an upright slot in one of its sides, an extension arm attached 35 to the other side of said yoke, and leading across the button and through said slot to

a remote point, and yielding means for holding the arm at that end of the slot which keeps it out of contact with the button, for the purpose set forth. 40

2. The herein described push button operator, the same comprising a yoke having an arched body adapted to overlie a push button and lateral feet whereby it may be fastened to a support astride said button, one 45 side of the yoke having an upright slot, ears within the other side of said yoke, an extension arm having one extremity pivoted between said ears and extending thence across the interior of the yoke and through 50 said slot to a remote point, and a spring carried by the yoke and bearing the arm to that end of the slot which holds it out of contact with said button, for the purpose set forth. 55

3. In an attachment for push buttons, the combination with an arched yoke adapted to be secured over the button and having an upright slot in one side, an extension arm pivotally connected with the opposite side and leading through said slot to a remote point, a spring normally holding the arm in that end of the slot which keeps said arm away from the button, and a contact member adjustably mounted on the arm between the sides of the 60 yoke and over the head of the button, for the purpose set forth. 65

In testimony whereof I affix my signature.

IRVAN NECKERMAN.
